UNITED STATES PATENT OFFICE

OSCAR ROTTINGHAUS, OF NORWOOD, OHIO

DEFLECTOR FOR WARM AIR FURNACE REGISTERS

Application filed June 4, 1930. Serial No. 459,162.

The invention relates to deflectors for register openings of warm air heating furnaces or systems and particularly to wall registers thereof.

6 An object of the invention is to provide a deflector and humidifier for warm air registers in the form of a cabinet adapted to be placed over a warm air furnace with the interior of the cabinet furnishing a passage 10 for taking in cold air at the base of the cabinet and communicating with the heated air passing through the upper portion of the cabinet for setting up and maintaining circulation of the air in the room at an increased velocity, increasing the heating efficiency.

Another object of the invention is to provide a cabinet form of warm air register deflector capable of being readily connected 20 interchangeably with different wall registers located at relatively different heights from the floor of the room in which the registers are disposed.

25 Various other objects and advantages of the invention will be more fully set forth in a description of the accompanying drawings, in which:

Figure 1 is a perspective view of the improved cabinet and deflector as applied over 30 a wall register of warm air conductor outlet of a warm air heating furnace.

Fig. 2 is a front elevation, partly a section, the section taken on line 2—2, Fig. 3.

35 Fig. 3 is a view of line 3—3, Fig. 2.

Fig. 4 is a detailed perspective view of a slide plate carried by the rear wall of the cabinet and extending therefrom for latching the cabinet to a wall register in making 40 an installation.

Referring to the drawings, 1 indicates a rectangular form of cabinet constructed of sheet metal, having an outlet opening 2 through the upper end of the front or face wall of the cabinet covered by a grating 3. The cabinet is open at its base and slightly elevated above the floor by legs 4 to admit air into the cabinet from below, and to circulate upwardly through the cabinet mixing 45 with the heated air also directed upwardly

through the cabinet from the hot air conductor with which the cabinet connects.

The lower portion of the cabinet is divided by a vertically inclined partition wall 5 connecting or engaging at its lower end 55 with the rear wall of the cabinet. The partition 5 provides a cold air passage 6 with an intake end of the full area of the cabinet, and a hot air passage with an intake through an opening in the rear wall of 60 the cabinet, and both communicating at a point above the hot air intake or to a point approximately midway of the height of the cabinet. The provision of separate hot air and cold air intake passages prevents the 65 incoming hot air from dampening the cold air.

The heated air heats the partition wall, heating the cold air within the cold air passage which is set in circulation upwardly 70 mixing with the hot air. The room, therefore, can be more readily and efficiently heated as the cold air which is present at the lower portion or floor of the room is drawn from the room into the cabinet and 75 heated and its velocity increased under the influence of the more rapidly moving heated air passing upwardly through the cabinet from the conductor of the furnace.

The rear wall 8 of the cabinet has an 80 opening 9 therethrough for connecting the hot air passage 7 of the cabinet with the warm air conductor 10 leading from the warm air furnace or pipe of a warm air heating system of the building. The conductor 10 is provided with the commercial register 11 flanging against the wall surface of the room. A plate 12 is slidably mounted against the rear wall of the cabinet within 85 guide channels and is provided with an offset portion 13 extending through the opening in the rear cabinet wall adapting the plate to be engaged beneath the face of the frame plate of the register, latching or locking the cabinet to the register and appropriately spacing the cabinet from the wall, the spacing corresponding to the thickness of baseboard 14.

The provision of the slide plate accommodates for making register connections dis- 100

posed or located at varying distances from the floor, and also prevents the escape of dust or dirt upwardly in the rear of the cabinet either as may be conveyed with the hot air or circulated upwardly from the room floor, protecting against soiling the wall of the room about the cabinet or register.

The cabinet at its upper end is provided with curved deflector 15 for directing the air forwardly toward the outlet opening and with a humidifier or water pan 16 removably seated within the upper end of the cabinet enclosed by a cover 17 removably engaged over the top of the cabinet. Suitable openings 18 are provided in the front or side walls of the cabinet above the water pan for the escape of moisture from the pan into the room.

20 The deflector in its cabinet form aside from its utilitarian features, lends itself to be manufactured with artistic lines as an article of furniture to add to the furnishings of the room in which it is placed.

25 Having described my invention, I claim:
A deflector for register openings of warm air heating furnaces, comprising, a sheet metal cabinet having an outlet opening through the upper part from its front wall, and an intake opening through its rear wall for connecting with the register opening, the lower half of the cabinet subdivided to provide a cold air passage opening to the full area of the base of the cabinet and communicating with the warm air passage above the warm air inlet.

In witness whereof, I hereunto subscribe my name.

OSCAR ROTTINGHAUS.
